UNITED STATES PATENT OFFICE.

JONATHAN MOORE AND WILLIAM H. WILKINSON, OF BROOKLYN, N. Y.

DESIGN FOR FOUNTAIN-BASINS.

Specification forming part of Design No. **6,644**, dated May 6, 1873; application filed April 19, 1873.

To all whom it may concern:

Be it known that we, JONATHAN MOORE and WILLIAM H. WILKINSON, of Brooklyn, Kings county, in the State of New York, have invented a Design for Fountain-Basins, of which the following is a specification:

The nature of the design is fully represented in the accompanying photographic illustration, to which reference is made.

There is a central hole, which is intended to be filled by a central stem or support. A is the space around it, which may be plane. B B B are concave shells, each striated in diverging lines and curling upward and outward at the inner edge, and changing into a flowing leaf, C, with scrolls D D at each side. The leaf spreads out and partially covers the in-

terior of the shell. E E E are spiral shells, mounted as represented between the shells B, the joint between being filled with an imitation of loose pebbles or shells G.

We claim as our invention—

A design for fountain-basin, composed of shells B E, with the scrolls D and leaves C, combined and arranged substantially as herein shown and described.

In testimony whereof, we have hereunto set our hands this 11th day of April, 1873, in the presence of two subscribing witnesses.

JONATHAN MOORE.

WILLIAM H. WILKINSON.

Witnesses:

ERNEST A. WALTER,
ALFRED MOSFORD.
